UNITED STATES PATENT OFFICE.

JARVIS M. ANDREWS, OF WOLLASTON, MASSACHUSETTS, ASSIGNEE, BY MESNE ASSIGNMENTS, TO TECHNICOLOR MOTION PICTURE CORPORATION, OF BOSTON, MASSACHUSETTS, A CORPORATION OF MAINE.

FILM ROLLER.

Application filed July 24, 1924. Serial No. 727,917.

This invention relates to rollers and more particularly to rollers for the guidance or conveyance of materials in sheet form, such as cinema films or the like.

5 In the handling of strips of film and other flexible sheet materials of which films are typical, it is frequently necessary to convey the sheet through a given path and at the same time to support and guide it 10 preferably with as slight an amount of contact as possible. It is also desirable that such contact shall be substantially devoid of friction, but that it shall be of sufficient force to effectively direct the course of the 15 strip and to substantially prevent its uncontrolled slippage from the desired path.

These conditions are appropriately represented by the passage of cinema films through coloring vats, as by the flotation 20 method, for the production of colored reproductions. Here, the additional consideration of the tracking or creeping of the color solution over the edges of the film is also encountered. The invention will 25 accordingly be described in its adaptation to such a purpose, as typical of the general purposes and circumstances of use for which it is applicable, as will more fully appear from the following disclosure.

30 A preferred embodiment of the invention, as adapted to this purpose, is represented in the accompanying drawings, in which:

Fig. 1 is a side elevation of the film-dipping mechanism with parts broken away;

Fig. 2 is a detail view of a roller parallel to the axis;

Fig. 3 is a similar view of a modified form of roller;

Fig. 4 is a similar view of another modification; and

Fig. 5 is a similar view of another modification.

45 Referring to Fig. 1, numeral 1 indicates a film-treating tank, containing the fluid bath 2 upon which is floated the film 3 guided by rollers 4 and 5 rotatably mounted upon the axes 6 and 7 in the supports 8 and 9, respectively, of the frame 10. In Fig. 2 the roller 4 (or 5) is shown having symmetrical concave conical surfaces 11 and 12 merging into a substantially cylindrical portion 13 at their apices and into surfaces of increasing slope, eventually extending

substantially radially outward from the axis 55 and terminating in flat surfaces perpendicular to the axis as in Fig. 3, or slightly convex conical surfaces 14 and 15, respectively, at their bases. Such radially extending surfaces or flanges constitute lateral 60 guides for a film passing over the roller and serve to positively prevent side-slipping thereof. In Fig. 3 a modified form of roller is shown in which the opposing symmetrical cone-shaped surfaces 11' and 12' 65 are convex, each meeting an annular flange 16 at their bases and joined together at their apices by the cylindrical portion 13'. Fig. 4 is a further modification intermediate 70 those shown in Figs. 2 and 3 in which the conical surfaces 11'' and 12'' are circular cones.

The functioning of the apparatus will now be described. The tank 1 being filled to a suitable depth with the treating fluid 2, the film 3 is conducted downwardly under rollers 4 and 5 and connected with any suitable feeding mechanism for drawing it continuously through the path so defined. Between its contacts with the guide rollers 4 75 and 5 the film floats upon the fluid, thus thoroughly wetting one side (as with a coloring dye solution) but preserving the other side completely dry.

In such a process, it is essential that after 80 being thus treated, the fluid shall not in any manner reach the untreated surface. This is especially difficult with cinema films on account of the sprocket-holes, which are provided along the edges and which tend to 85 pick up pellicles of the liquid. These pellicles burst if they come into contact with the roller and are likely to spatter upon the dry side, thus spotting it and ruining the whole 90 film for further use, but if the pellicles are not touched they may be removed toward the wet side by suction or an air blast without spattering upon the dry side of the film.

The present invention obviates any such 100 contingency, by supporting the film while passing over the guide rollers upon its edges only. The longitudinal flexure of the film as its course is bent by the roller prevents the film from flexing transversely so that 105 the film during the period of contact with the roller remains substantially straight transversely.

When successive rollers are properly aligned there is little tendency for the film to slip out of its position of parallelism with the axis of the rollers. But if such a movement should occur, and one edge of the film slides downwardly upon its conical surface toward the center, the other edge is thrust upwardly accordingly upon the opposite bearing surface. This upward thrust increases with the amount of displacement of the film against it and eventually overcomes the friction on the opposite edge, forcing the raised side of the film backward toward the center.

Thus in Fig. 3 if the film were to be displaced to the position 3', as the edge of the film supported upon the surface 11 descends toward the center of the roller the opposite edge will be forced to ride up upon the surface 12, which is of increasing slope until it merges into a plane perpendicular to the axis of the roller as a limit which will positively prevent further slippage. But before reaching this limit the tendency will be for the edge of the film on surface 11 to slip back and the film as a whole to resume its former position.

Obviously, the exact dimensions and curvatures which will be employed in any given case will be determined by the particular circumstances involved. In some cases, the curvature may be convex as in Fig. 3, especially for less rigid sheets, or it may have an intermediate position, as represented by the right circular cones shown in Fig. 4.

Other modifications and adaptations of the invention will be suggested by the above disclosure. For example, Fig. 5 illustrates a modification in which narrow ledges 21 are provided at the junctions between the conical surfaces 22 and the flanges 24. It will also be evident that the invention is applicable wherever it is necessary to guide and convey a flexible sheet through a given path without contacting with the side portions of the sheet. Such adaptations are to

be considered as comprehended by the present specification and the following claims.

I claim:

1. A roller for guiding a strip of resilient material, having opposed strip-engaging surfaces tapering toward each other and terminating at their remote edges in a surface extending substantially radially from the axis, whereby the engagement of the strip with the roller is confined substantially to the edges of the strip.

2. A roller for guiding a strip of resilient material, having opposed strip-engaging surfaces tapering toward each other, and radial flanges at the outer ends of said surfaces, the inclined surfaces normally engaging the edges of the strip and the flanges preventing the strip from running off the inclined surfaces.

3. Apparatus for guiding a strip of resilient material along a predetermined path comprising a series of rollers having conical strip-engaging surfaces tapering toward each other, and of increasing slope on their remote or lateral edges, constituting lateral guides for retaining the strip on said surfaces as it is advanced along said path.

4. Apparatus for guiding a strip of resilient material along a predetermined path comprising two guide rollers and means between the rollers for wetting one side of the strip, the roller with which the strip contacts after being wet having conical strip-engaging surfaces for guiding the strip by edge engagement.

5. A roller for guiding a strip of resilient material, having opposed surfaces shaped to support the strip by contact confined substantially to the edges of the film, and lateral guides extending substantially radially from the axis thereof for retaining the film on said surfaces.

Signed by me at Boston, Mass., this ninth day of July, 1924.

JARVIS M. ANDREWS.
